RADIO RECEIVING SYSTEM

Harry J. Nichols, Henry C. Forbes, and Walter S. Harmon, Dayton, and Homer J. Loftis, Ironton, Ohio, assignors, by mesne assignments, to Radio Corporation of America, New York, N. Y., a corporation of Delaware

Application March 4, 1932, Serial No. 596,732

6 Claims. (Cl. 250—20)

This invention relates to universal remote control unit for radio receivers and has for an object to provide a flexibly attached device to be used in conjunction with any radio wave translating device whereby the same may be controlled fully in accordance with the desires of an attendant.

Another object of the present device is to provide a remote control unit that will improve the radio reception. This has been accomplished by adding a device to a receiver that incorporates selective devices or circuits and the heterodyne principle.

Another object of this invention is to improve the sensitivity of a radio receiver. This may be accomplished by the signal amplification gained in the remote control unit.

Another object of this invention is to provide selective means at the remote control unit that limit the output to the selected signal and reduce the image response. This has been accomplished by providing a signal utilization device in the remote control unit.

Another object of this invention is to utilize the incoming signal at the remote control unit to produce a resultant wave of different frequency for amplification. This has been accomplished by mounting an oscillator in the remote control unit whose product combines with the incoming signal to form a beat frequency.

Another object of this invention is to provide a control mechanism in a remote control unit that tunes a band pass filter and actuates an adjustable device of an oscillator so that the frequency of a beat signal is constant regardless of the setting of the band pass filter. This has been accomplished by actuating the tuning devices in the band pass filter simultaneously with the adjustable device in the oscillator.

Another object of this invention is to use a radio receiver, having its tuning devices set at a predetermined position, in conjunction with a remote controller for receiving any one signal within the range of the tuning device of the remote control unit, without the need of thereafter changing the tuning devices on the said radio receiver. This has been accomplished by mixing the incoming signal with another wave to produce a resultant that is transmitted to and reproduced by the receiver.

Another object of this invention is to provide means for producing in the remote control and means for efficiently transmitting between the remote control and receiver, signal energy having a predetermined fundamental frequency. This may be accomplished by providing simultaneous tun-

ing of an oscillator and selective means in the remote control and tuning the transmission line to be efficient at the frequency of the resultant signal.

Another object of this invention is to provide means for flexibly attaching a movable control unit to any radio reproducing device. This may be accomplished through the use of properly constructed wire connections.

Another object of this invention is to provide means for remotely controlling a radio receiver that does not radiate energy or pick up stray signals or noises within itself. This may be accomplished through the proper construction and shielding of the unit and the transmission cable.

Another object of this invention is to prevent distortion of the output signal caused by disturbing signals being impressed upon the incoming signal and the signal transmitted from the remote control unit to the radio receiver. This has been accomplished by shielding the appropriate leads.

Another object of this invention is to provide means for tuning the transmission line in such a way that it will be most efficient at some predetermined frequency. This may be accomplished as disclosed by utilizing the capacity between the shield and line and other capacity in such a way that the whole output circuit is tuned to the desired frequency value.

Another object of this invention is to provide a transmission line together with suitable matching devices that will not appreciably attenuate the signal voltage impressed upon the remote control unit. This has been accomplished by providing a transformer or impedance matching device that matches the impedance of the antenna with the impedance of the line at some desired frequency and using a second impedance matching device to condition the signal received to be used by a translation device.

Another object of this invention is to provide means in the remote control unit so that the advantages of the heterodyne principle of reception may be applicable to tuned radio frequency receivers and the advantages of two intermediate frequencies applicable to superheterodyne receivers. This may be accomplished as herein disclosed by incorporating an oscillator and detector in the remote control unit.

Another object of this invention is to provide means for lighting the tubes and an illuminating device in the remote control unit. This has been accomplished by providing a transformer in the remote control unit energized from the regular source of lighting circuit.

Another object of this invention is to provide means for a dual control, so that the energy output of the radio receiver may be controlled at the remote unit. This has been accomplished by providing a volume control in the remote control unit that controls the output of the radio receiver.

Another object of this invention is to provide means for controlling the output of the receiver as well as the signal response frequency from the remote control unit. This may be accomplished by providing a suitable control in the remote unit for the output of the receiver.

Another object of this invention is to provide a switching mechanism whereby the antenna may be connected either to the radio receiver or to the remote control unit. This has been accomplished by providing a switch that connects the antenna to the input terminals of the radio receiver in one position and that connects the antenna to the remote control unit in another position.

Another object of this invention is to utilize the antenna that supplies the signal to the radio receiver whereby a separate antenna need not be provided for the remote control unit. By so doing it is possible to use the antenna circuit either for the radio receiver without the remote control or with the remote control.

Another object of this invention is to provide a remote control which is capable of making possible the reception of signals outside of the ordinary broadcast band, with a receiver built for use within the broadcast band range only. This may be accomplished by the use of interchangeable coils for use in the control unit.

Further objects and advantages of the present invention will be apparent from the following description, reference being had to the accompanying drawings wherein a preferred embodiment of one form of the present invention is clearly shown.

In the drawings:

Fig. 1 discloses a remote control unit attached to any radio receiver of conventional design.

Fig. 2 discloses a plan view of the remote control unit casing.

Fig. 3 is a bottom plan view of the remote control base.

Fig. 4 is a detail view of a remote control cable. Fig. 5 is a sectional view thereof.

Fig. 6 discloses a schematic wiring diagram of the circuit arrangement used in the remote control unit and its connections to one type of a standard receiver.

Fig. 7 discloses a similar diagram of the circuit and its connection to another type of receiver.

Fig. 8 discloses a modified form of the remote control unit, embodying a modification in the volume control means, and additional selective and amplifying means.

With particular reference to the drawings, Fig. 1 illustrates the physical embodiment of the remote control device and its adaptation to one type of receiver. Here the remote control unit 10 is connected by a suitable cable 32 with the radio instrument or other wave translation device 12, which houses any suitable radio receiver and that may embody either of the receiver circuits illustrated in Figs. 6 and 7 or any modification thereof. For purpose of illustration the receiver circuit is indicated at 13 and presumably is provided with the necessary stages of detection and amplification 15, as well as a pow-

er pack or transformer 17 and whose signal output is made use of by a loud speaker, reproducer or equivalent device 19. Since the type of receiving circuit with which the remote control unit is to be used is substantially incidental, except as set out in a later paragraph, it is not believed necessary to go further into description of the same except as will hereinafter follow where reference will be made to the detail application of the remote control unit with the said receivers. 10

However, the detailed depicting of different circuits in Figs. 6, 7, and 8 have their application to illustrate the universal adaptation of the remote control unit to any desired type of receiver. With this explanation suffice it to say that 15 the receiving circuit illustrated in Fig. 6 is designed to illustrate the adaptation of a remote control unit to a receiver fitted with manual control for the receiver output, while Fig. 7 is illustrative of an adaptation to a receiver having 20 automatic control for the receiver output. On the other hand, Fig. 8 is illustrative of a remote control unit embodying a volume control tube.

The remote control unit 10 disclosed may be used with practically any modern or proposed 25 radio receiver 12 which may be a tuned radio frequency receiver, a superheterodyne receiver, a super-regenerative receiver or the like. However, instead of using a radio receiver provided with selective tuning devices, a receiver having its elements secured at a fixed setting may be constructed for use in connection with the remote control unit and can be used as will presently appear. As disclosed in the drawings a casing 14 is provided, within which is housed a detector 16, an oscillator 18 and an appropriate circuit incidental thereto. The particular circuit adopted is that illustrated in Fig. 6 or 7, and is explained as follows. The numeral 20 is indicative of an antenna which is usually connected to the 40 receiver 13. Provision is made for connecting the antenna with a transformer 22, and it is desired to incorporate a switching mechanism 24 in this connection for purposes, and the structure of which will presently appear. 45

The transformer 22 is preferably a step-down transformer whose purpose it is to match the impedance of the antenna to that of the line at or near the high frequency end of the band of signals to be received. The primary winding 26 of the transformer 22 is connected in the antenna circuit and grounded at 28. The transformer 22 is preferably located near the aerial post in the radio receiver so as to have a more or less direct connection with the said antenna. The secondary winding 30 of the transformer 22 has one terminal grounded at 28 and the other terminal connected to a lead 31 located within a cable 32 shown in Fig. 1, communicating with the remote unit. The lead 31 is an insulated conductor and is shielded by a metallic shield 33 having its ends grounded at 28 and 34, so that no stray impulse is picked up by the lead 31 as the signal is transferred from the transformer 22 to a transformer 36. The transformer 36 has its primary 38 connected in series with the lead 31 and is grounded at 34. Since the transformer 22 matches the impedance of the antenna to that of the line preferably at or near the high frequency end of the band, the transformer 36 70 matches the impedance of the line to that of the input circuit of the remote control, preferably at or near the low frequency end of the band of signals to be received. It is understood, however, that the points of matching the impedances might 75

be reversed or shifted and still come within the spirit of the invention. The description set forth here is merely an example of a method of obtaining uniform signal attenuation over the range of frequencies to be received, and also to obtain low losses.

Another method of accomplishing the same advantage of uniform signal attenuation and low losses over the range of frequencies to be received, is to match the impedances at the same and preferably at or near the low frequency end of the band, and then to use a low impedance input circuit at the remote unit. In other words, the impedances matched by transformers 22 and 36 are matched at a low frequency and the impedance of coil 42 of the transformer 44 is made low.

The secondary winding 40 of the transformer 36 has one terminal grounded at 34 and the other terminal connected to the primary winding 42 of a transformer 44 that is also grounded at 34. This transformer is provided with a secondary winding 46 and is connected in parallel with a tuning condenser 48, and a fixed mutual condenser 50 to form a closed resonant loop. At a point intermediate the terminals of the elements 48 and 50, the loop is grounded at 52. An inductance 56 and a variable condenser 58 together with the mutual condenser 50 forms a second resonant loop and cooperates with the first loop that includes the inductance 46 and the condensers 48 and 50 to form a band pass filter 60, and which has a double peaked resonant curve whenever a proper value is selected for the mutual condenser 50. At a point intermediate the condensers 58 and 50 connections are also made to ground at 52 and from this same or similar intermediate point a resistance 64 is inserted and connected across the condenser 59 so as to be in series with the inductance 56 and ground.

The output of the band pass filter 60 is connected to a grid 62 of the detector 16, so that the direct current path of the grid circuit extends from the grid 62 through the inductance 56 and 45 through the resistance 64 that is also grounded at 52. As the resistor 64 has a very high resistance as compared to the condenser 50, the resistance 64 does not materially influence the shape of the resonance curve of the band pass 50 filter 60. The signals selected by the band pass filter 60 are combined with locally generated oscillations produced by a device to be described, so that the radio frequency signal passing from the detector 16 through a lead 70 to the input 55 terminal 71 of the radio receiver 13 is of different frequency from the incoming signal.

The device for producing the locally generated oscillations, includes an oscillating tube 18 having its grid 72 connected at an intermediate point 60 74 of an inductance 76, through a condenser 78 connected in series with a resistance 80. An adjustable condenser 82 and a variable condenser 84 are connected together in series, and thence are connected in parallel with the inductance 76, 65 to form a resonant circuit inductively coupled to a coil 86 in the plate circuit of the oscillator 18, and also inductively coupled to a coil 88 located in the circuit of the detector cathode 90 that is grounded through a resistance 92 at 94. The 70 resistance 92 supplies a bias to the cathode 90 of the detector 16, and the by-pass condenser 96 forms an alternating current path shunted about the biasing resistance 92.

Returning to the oscillator 18, its cathode 100 75 is connected to one terminal of the resonant cir-

cuit including the inductance 76 connected in parallel with the condensers 82 and 84 and grounded at 102. A grid leak resistor 104 has been connected intermediate the grid 72 and the cathode 100. From this it can be readily seen that as 5 oscillations are set up in the oscillator, including the tube 18, that these oscillations will be transferred to the cathode 90 of the detector 16, so as to combine with the incoming signal to form a beat signal having a frequency that is either the 10 sum of or the difference of the incoming signal and the locally generated oscillations.

A plate or B potential is supplied to the plate 110 of the detector 16 by the B source from the radio receiver through a lead 112 carried by the 15 cable 32 and through an inductance 114. The lead 112 also supplies a B potential to the plate 116 of the oscillator 18, and to the screen 120 of the detector 16, through the resistance 118. The resistance of the inductance 86 in series with 20 plate 116 is so low that the potentials on the plate 116 and the screen 120 are substantially equal. Condensers 122 and 124 have their terminals connected intermediate the plate circuit and the screen grid circuit and are grounded at 25 125 to provide by-pass circuits for the alternating current component.

As far as possible it is desirable to control the volume output of the receiver at the remote unit so that no adjustment will be required of the 30 volume output at the radio receiver. This may be accomplished in diverse ways but the preferred form of volume control for this purpose as disclosed in Figs. 6 and 7, includes a resistor 130 having one terminal connected intermediate the 35 high potential terminal of the secondary winding 40 of the transformer 36, and the high potential terminal of the primary winding 42 of the transformer 44. An adjustable tap 132 short circuits a part of the resistance 130 and is grounded at 40 142 so as to form a by-pass circuit for a portion of the signal if it is desirable to reduce the magnitude of the incoming signal. Thereby the volume of the signal may be controlled by adjusting the tap 132 on the resistor 130. A lead 134 from 45 the resistor 130 may, if it is found necessary, be connected to a suitable volume control in the radio receiver as illustrated in Fig. 6.

In addition to the volume control already described, another volume control mounted for operation by the same control knob 136 may be used to control the potential supplied to certain other grids, or other elements in the radio receiver, depending upon the particular design of the radio receiver used. This volume control 50 includes a resistor 140 having one terminal grounded at 142 and a lead 143 for connection to the receiver. An adjustable tap 144 may be adjusted along the resistor 140 to change the bias supplied to certain control elements found within the 55 radio receiver, a lead 146 with the lead 143 providing for that connection. The detailed circuit of the volume control in the radio receiver may be connected in either instance as illustrated.

The remote control unit thus provides a dual 60 volume control such that the unit may be adapted to practically any type of radio receiving device, whether the receiver be one fitted with only a manual control for the volume output or whether the receiver incorporates means for automatic 65 volume control. The adaptation of the remote unit to a receiver of the first type is fully illustrated in Fig. 6 where the lead 134 from the resistor 130 makes connection with the volume control 214 of the receiver substantially as will be 70 75

described in a later paragraph with respect to the multiple circuit switching mechanism. It will be noted that the volume control means provided by the remote unit is substantially divided in half, the first portion 130 of which is designed to be connected into the receiver circuit as will presently appear, while the second portion 140 may be connected into a receiver providing for automatic volume control as illustrated in Fig. 7.

In the latter instance, or where the set is provided with an automatic volume control, one-half of the dual control of the remote unit is connected in the circuit of the receiver preferably by carrying the lead 143 to one terminal 145 of the secondary in the reproducer device 19, and by disconnecting the lead joining the voice coil, usually connected to the said secondary at this point, and joining it to the lead 146 communicating with the adjustable tap 144 on the resistor 140. For best results, the other lead joining the secondary of the device 19 and its voice coil should be provided with a ground connection as at 147. It may also be found desirable to 25 connect the portion 130 of the volume control in the remote unit, which may be accomplished by severing the lead 149, substantially as indicated at 151. In either instance, that is to say, whatever adaptation of connection between the remote unit and the receiver is made, means are provided for fully controlling the volume output of the receiver from the remote unit, and the volume control in the remote unit is superimposed upon that contained in the receiver and makes 35 for complete control thereover.

Still another modification of the volume control which may be applied to the remote control unit is disclosed in Fig. 8. As will be apparent from the following description, this form of control in addition to giving the desired volume control also adds additional amplification to the remote unit as well as additional selective means to the system. Since the detector and oscillator circuits of this modification are essentially the same as those previously disclosed similar reference numerals have been applied to the parts in this modification.

The plate 110 of the detector 16 is coupled to the input of a thermionic tube 75 through a 50 tuned transformer 61. The potential on the plate 110 of the tube 16 is supplied through a primary 63 of the transformer 61 from the receiver unit through lead 112. The primary 63 is tuned by a condenser 65 to be resonant at the intermediate 55 frequency. Resistors 69 and 71, which are in series and connected at one end to lead 112 and grounded at the other end at 73, form a voltage divider which supplies the potential to the screen grid 120 through its connection to the common 60 terminals of the resistors. The condensers 124 and 122 connected to the screen grid 120 and lead 112 respectively, and ground at their common terminal at 126, form high frequency bypasses for those circuits. A secondary 67 of the 65 transformer 61 has one end connected to a grid 79 of the tube 75 and its other end grounded at 81. A condenser 77 tunes the secondary 67 to resonance at the intermediate frequency. The potential on a screen grid 85 of the tube 75 is supplied from the common terminals of resistors 69 and 71, and the potential on a plate 83 of the same tube is supplied from the lead 112 through the choke coil 114. The heater-lighting potential is supplied from the transformer secondary 163 70 as for the other tubes. A resistor 87 is con-

nected in series with a cathode 95 of the tube 75 and establishes the minimum bias to that tube and is also in series with the volume control 130 having the movable contact 132 and grounded at 142. Hence by varying the position of the movable contact 132 of the volume control 130 the bias on the grid of the tube 75 is varied. That is, the greater the resistance between the end of the resistor 87 and the movable contact 132 the more negative the bias of the tube. Since one end of the volume control 130 is also connected by the lead 149 to a point intermediate the coil 40 and coil 42, that control serves a dual purpose. At the same time as the bias on tube 75 is increased, which tends to reduce the volume, the signal input 15 to the unit is decreased by the decrease in resistance across the signal input circuit. Thus the two controls are complementary. A condenser 89 connected to the cathode 95 and grounded at 91 forms a bypass for the bias resistor 87 and volume control 130. Plate 83 of tube 75 is connected with the receiver through the condenser 154 and the shielded line 70, which transfers the signal to the receiver unit, as previously described.

It may now be seen that addition of the transformers 61 and tube 75 to the remote control unit, give additional amplification to the unit and adds additional selective means, since the signal in the plate circuit of the tube 16 has a predetermined frequency value and the transformer 61 is 30 tuned to resonance at that frequency. It transfers the signal to the grid 79 of tube 75 at its point of maximum efficiency.

Then the signal in the plate circuit of the tube 75 has the same fundamental frequency as that 35 in the plate circuit of the detector 16. The line 70 may be tuned by the condensers 154 so that maximum voltage is developed between the lead 70 and the shield 152 which surrounds it. Since it is the voltage between lead 70 and the shield 40 152 which is applied to the input of the receiver, the tuning of that line by the condenser 154 makes that voltage transfer between the remote unit and the receiver more efficient. This modification may preferably be used with the receiver 45 unit, such as that shown in Fig. 6, but may very well be used with the receivers of the type shown in Fig. 7.

The structure thus far described is substantially that enclosed within the casing 14 of the 50 remote control unit 10 illustrated in Fig. 1. The unit also houses a transformer 150 that is conveniently mounted in the base thereof as indicated in Figs. 1 and 3, and has its primary winding 152 connected by appropriate leads 154 and 55 156 included in the multi-conductor cable 32 from whence they make connection with a series plug 153. At an appropriate point 160 in the conductor 154 there is provided a contact terminal, and a switch 162 that optionally contacts there-with and joins a terminal 164 connected to a third lead 166 that also has communication with the series plug 153 as will presently appear. The secondary 163 of the transformer 150 is provided with conductors 170 and 172 to which connection 60 is made with the filaments 174 of the detector and 176 of the oscillator for lighting the same. Inasmuch as there are many lines in the drawings it is deemed sufficient to make this statement without showing the actual connection in both circuits, believing it to be obvious to one skilled in the art how these connections may be made simply by referring to Fig. 7. A dial light 178 is connected across the leads 170 and 172 and in series 65 with an appropriate resistor 180. One terminal 70 75

of the secondary 168 has connected thereto a conductor 182 that joins the shield 152 of the conductor 78 and is eventually grounded at 156.

The structure thus far described constitutes the essential portions of the remote control unit according to the adaptation that has been made, and when reference is had to Fig. 6 of the drawings it will be seen that it is in main all of that structure to the left hand side of the terminal strip indicated at 186 and shown in dashed lines. For convenience it may be regarded that the terminal strip 186 is indicative of the content of the multi-conductor cable 32 which carries some 7 or 8 leads or conductors providing the various communications between the remote unit and the receiver to which it is to be attached, all of the receiver structure being indicated as having its various connections coming in from the right hand side of the terminal strip 186.

Inasmuch as the remote unit is designed for universal adaptation to practically any type of radio receiver, and since it may be desirable in some instances to control the receiver without the remote unit, provision is therefore made for accomplishing those results, which, it is believed are fully illustrated in the circuit diagram in Fig. 6. The universal adaptation of the remote unit to that type of receiver is illustrated by example in Figs. 6 and 7 though it will be obvious to one skilled in the art that the remote unit may be connected into the circuits of other receivers than the two particular types illustrated. To save confusion of illustration and so as to make use of as few lines as possible the provisions for using the receiver without the remote control unit has been illustrated only in Fig. 6, it being obvious to one skilled in the art that the same principles can be, or are to be observed when this feature is applied to any other receiver than that illustrated in Fig. 6.

In illustration of the latter feature, a multi-circuit controlling switch is provided and for purpose of illustration may include the shiftable contact members 190, 192, and 194 that cooperate with contact members 198, 200, 204, and 206 respectively, the movable elements being manually and coincidentally operable by a knob or button 210 fixed upon a common shaft or operating member 212 indicated by dot-and-dash lines. In further explanation of this switch it will be observed that the movable element 190 is joined to the lead-in wire from the antenna 20 and is movable from a position to engage the contact 198 to a position in which it engages the contact 200, and likewise the movable element 192 is moved from a position engaging the contact 200 to a circuit open position. Also the movable element 194 is engageable with either of the contacts 204 or 206 so as to make the proper changes in the circuit with regard to the volume control of the receiver. By this structure diagrammatically illustrated, the attendant is permitted by manipulation of the knob 210 to connect in the remote unit so as to fully control the receiver, or he may entirely sever that unit in its operative connection with respect to the receiver. The full line position of the movable elements of the switch indicates the connections when the remote unit is to act as a controller for the receiver, while the dotted line position indicates the connections that are made when the receiver is to be used without the remote unit.

When the remote unit is to be used in connection with a radio receiver such as appears

by the full line position of the multi-circuit switch illustrated in Fig. 6, the antenna 20 is then connected through the movable element 190 with the contact 198 from whence the incoming signal picked up by the antenna 20 passes through the transformer 22 and thence is impressed upon the signal utilization device of the remote unit, from which the conductor 78 returns the signal output and by reason of its connection with the movable element 192 in engagement with the contact 200 impresses the signal upon the input terminal 71 of the receiver 15. The volume control element 138 has connection by its lead 134, and the movable element 194 that is then in engagement with the contact 204, with the volume control element 214 contained within the receiver by which the audible output of the receiver is controlled.

With the connections thus made, and with the series plug 158 attached to the source, and with the plug 220 of the power unit 17 properly attached and with the instrument control switch 222 and the remote control switch 162 being closed, the remote unit and receiver are in proper hook-up to provide for complete control of the receiver 13 by the remote unit 10.

When it is desired to use the receiver without the remote unit the multi-circuit switch is moved to the dotted line position in which all of the essential connections between the remote unit and the receiver are severed, and in which the antenna 20 is directly connected with the input terminal 71 of the receiver by reason of the movable element 190 engaging the contact 200 and the movable element 194 being in engagement with the contact 206, whereby the proper ground connection is made from the volume control 214 to ground at 224. It will be noted that in this dotted line position the connection over the lead 79, from the plate of the detector to the terminal 71 of the receiver is open circuited, thus disqualifying the signal output of the remote unit. Opening of these circuits will not wholly deenergize the transformer 150 and will not affect the source of energy impressed upon the power unit 17, inasmuch as the series plug 158 has provision by means of the switch 162 for completing the circuit through the said power unit from the elements 216 and 218 irrespective of the open or closed condition of the said switch. While this will cause the filaments of the remote unit to still hum, it may be overcome if objectionable by withdrawing the series plug 158 from the source and inserting the plug 220 in its place.

When the remote control unit is used in connection with a radio receiver having tuning devices, those devices are set in some predetermined position, as for example to a wave length somewhat outside of the usual broadcast range, or even to a wave length within the range that is relatively spaced from other waves in the assignment of stations.

It is preferred, however, to tune the receiver to a point just beyond the low frequency end of the broadcast band, say 535 kilocycles. When the receiver is tuned to that frequency the oscillator will track the first detector tuning in the remote control unit, and the dial thereof will read correctly in frequency. It is obvious, that when the receiver has its tuning devices set at some other point on the band, that the remote unit may be constructed or adjusted to operate most efficiently at that predetermined receiver setting.

The remote control unit as here disclosed contains a band pass filter used as a station selector,

with an oscillator 18 and a detector 16. Either a 5 separate oscillator and detector, or a single tube oscillator and detector may be used, so that a heat frequency can be produced by combining the desired incoming signals with locally generated oscillations equal to the frequency for which the receiver is set. The incoming signals may be 10 signals within the usual broadcast range of the radio receiver, or signals outside of the usual broadcast range generally referred to as short wave signals. In the latter instance the remote control unit can of course be provided with interchangeable coils, so as to change its range from the usual broadcast range to the short wave range, 15 and vice versa.

To accomplish the greatest efficiency of the apparatus at least two of the leads contributing to the cable 32 communicating between the receiver and the remote unit are provided with 20 metallic shields. One of these is lead 31 that is enclosed in its shield 33, one end of which is grounded at 34 by means of an appropriate connection 184, and the other end of which may 25 metallically join a shield 230 disposed about the transformer 22, which may have its ground connection completed by a lead 232 from the ground 28 in communication with the shield 33, or else the shield 230, and this grounding may be made more certain by extending the lead 232 with a lead 30 234 having communication with a ground post 236 provided by the receiver. Likewise the lead 70 extending from the plate 110 through the condenser 154 is provided with a shield 152 and grounded at 156. All of the ground connections found in 35 the remote control unit are grounded to the remote control casing 14 substantially as indicated, and which in turn may be connected by a ground wire to the ground terminal of the radio receiver.

The operation is believed to be obvious from the 40 structure that has been heretofore described, and it is thought to be apparent that when the remote unit is attached to the receiver that the entire control of the receiver, whether it be tuning 45 control or volume control, may be accomplished from the remote unit. The remote unit being flexibly attached to the receiver makes provision for using practically any type of receiver whether it be one of the tunable type or one of fixed setting, which receiver may be stowed away 50 in any convenient or available space and operated without further attention being given to it than merely to manipulate the remote unit.

The mechanism within the remote unit provides 55 selective means for limiting the output of a selected signal and reduces the image response through the operation of the signal utilization device. By mounting the oscillator in the remote unit and combining its product with the incoming signal there is produced a wave of different 60 frequency in the form of a beat frequency, which when transmitted to the receiver may be amplified. This is accomplished by controlling in unison the tuning of the band pass filter and the oscillator device. Thus signal energy produced 65 in the remote unit is then transmitted to the receiver through an appropriate transmission line.

The line joining the remote control with the receiver is so constructed by shielding both the unit and the transmission cable that there will 70 be no radiation of energy, nor will there be any pick-up of stray signals and other noises. The shielding of the leads also prevents distortion of the signal put out over the line 70, and the tuning of this out put-lead makes for the greatest efficiency at a predetermined frequency. This in

main is accomplished by the trimmer condenser 154, by which the capacity existing between the shield and line is controlled and may operate to tune the line to the desired frequency value. By incorporating the line matching devices, that is 5 to say, the transformers 22 and 36, the signal voltage impressed upon the remote unit will not be objectionably attenuated, and by interposing one of the line matching devices between the antenna and the receiver, the need for providing 10 a separate antenna for the remote unit is obviated. The multi-circuit switch inserted in the disclosure of Fig. 6 provides for this dual use of a single antenna as well as permitting the use of 15 the receiver either with or without the remote unit.

It will be further noted that adaptation is made of the superheterodyne principle, particularly in the instance where the adaptation is made as depicted in Fig. 6, due to the incorporation of an oscillator and the detector in the remote control unit, for in fact the remote unit may be considered as a superheterodyne converter. Provision is therefore made for controlling from a remote point a receiver having its 20 tuning devices set at some predetermined position. The detector and oscillator within the remote unit provide for the mixing of the incoming signal with another wave to produce a resultant that is transmitted to and reproduced by 25 the receiver, and these two devices with perhaps also the tuning device of the remote unit in effect add just so much to the standard receiver and thereby operate to improve the radio reception. Due to the signal amplification gained 30 in the remote unit the sensitivity of the receiver is also improved.

While the form of embodiment of the present invention is herein disclosed, constitutes a preferred form, it is to be understood that other 40 forms might be adopted, all coming within the scope of the claims which follow.

What is claimed is as follows:

1. A system for receiving broadcast signals transmitted within a band of frequencies, said system including a radio receiver having an antenna, said receiver having a selective input resonant to a frequency below the broadcast range, a remote control unit, means for transmitting all of the incoming signals received by 45 the antenna to the remote control unit, said means comprising a transmission line electrically connected between the antenna and the remote control unit through means acting to match substantially the impedance of the antenna to the 50 impedance of the line in the vicinity of one end of the band of frequencies to be received, means at the remote control unit for selecting a predetermined signal for amplification, a device in the remote control unit for changing the frequency of the selected signal to a fixed frequency 55 equal to said first frequency, and means for transmitting the fixed frequency signal to the radio receiver, whereby the radio receiver amplifies such predetermined fixed frequency.

2. A system for receiving broadcast signals transmitted within a band of frequencies, said system including, a radio receiver having an antenna, said receiver having a selective input fixedly resonant to a frequency below 550 kilo- 70 cycles, a remote control unit, means for transmitting the incoming signal from the antenna to the remote control unit, said means comprising a transmission line, one end of which is electrically connected to the antenna through means 75

acting substantially to match the impedance of the antenna to the impedance of the transmission line in the vicinity of one end of the band of frequencies to be received, the other end of the transmission line being electrically connected to the input circuit of the remote control unit through means acting to substantially match the impedance of the line to the impedance of the input circuit of the remote control unit in the vicinity of the other end of the band of frequencies to be received, means in the remote control unit for changing the incoming signal to a signal having a frequency equal to said first frequency, and means for transmitting said changed frequency signal from the remote control unit to the radio receiver.

3. A remote control unit for a radio receiver comprising in combination, a detector having its plate circuit connected to the input terminal
20 of said radio receiver, an oscillator for generating oscillations of a desired frequency range, means extending from the aerial of the radio receiver to the detector for impressing the incoming signals upon the detector, said means comprising a transmission line, one end of which is electrically connected to the antenna through means acting substantially to match the impedance of the antenna to the impedance of the transmission line
25 in the vicinity of one end of the band of frequencies to be received, the other end of the transmission line being electrically connected to the input circuit of the remote control unit through means acting to substantially match the impedance of the line to the impedance of the
30 input circuit of the remote control unit in the vicinity of the other end of the band of frequencies to be received, and means for impressing the locally generated oscillations upon the detector, said oscillator and signal frequency
35 ranges being such that a beat frequency of the order of 535 kilocycles is transmitted from the detector plate circuit to the input terminal of the radio receiver.

4. A remote control unit for a radio receiver
45 comprising in combination, a detector having its plate circuit connected to the input terminals of said radio receiver, an oscillator for generating oscillations, a high frequency conductive path extending from the antenna of the radio receiver
50 to the detector for impressing the incoming signals upon the detector, said means comprising a transmission line, one end of which is electrically connected to the antenna through means acting substantially to match the impedance of
55 the antenna to the impedance of the transmission line in the vicinity of one end of the band of frequencies to be received, the other end of the transmission line being electrically connected to the input circuit of the remote control unit
60 through means acting to substantially match the

impedance of the line to the impedance of the input circuit of the remote control unit in the vicinity of the other end of the band of frequencies to be received, means for impressing the locally generated oscillations upon the detector, whereby a beat frequency is produced, and means for transmitting the beat frequency to the radio receiver including a tunable amplifier element for improving the efficiency at a predetermined frequency.

5. Radio receiving apparatus comprising a plurality of units, one of said units including amplifying, detecting and reproducing means, another unit having tuning means, an oscillator, a non-oscillating detector, and an amplifier, means providing bias for the amplifier, a cable connecting said units and including one or more shielded leads, and means tuning one of said leads to be efficient at a predetermined frequency, said amplifier having means for limiting the bias to a predetermined minimum value and means for varying the bias negatively from that minimum value, said bias variations serving to control the signal volume transmitted between the units by the cable. 25

6. A system for receiving broadcast signals, said system including a radio receiver having an antenna, the receiver having a selective input resonant to a frequency below the broadcast range, a remote control unit for the receiver, means for transmitting all of the incoming signals received by the antenna to the remote control unit, said means comprising a transmission line, one end of which is electrically connected to the antenna through means acting substantially to match the impedance of the antenna to the impedance of the transmission line in the vicinity of one end of the band of frequencies to be received, the other end of the transmission line being electrically connected to the input circuit of the remote control unit through means acting to substantially match the impedance of the line to the impedance of the input circuit of the remote control unit in the vicinity of the other end of the band of frequencies to be received, means at the remote control unit for selecting a predetermined signal of the broadcast range for amplification, a frequency changer device in the remote control unit for changing the frequency of the selected signal to a fixed frequency equal to the first-named frequency, means for transmitting the said fixed frequency signal energy to said radio receiver whereby the radio receiver amplifies said fixed frequency, and said receiver including a detector for demodulating the amplified fixed frequency. 55
